FRED P. DANZER, OF RACINE, WISCONSIN, ASSIGNOR TO GOLD MEDAL FOLDING FURNITURE COMPANY, OF RACINE, WISCONSIN, A CORPORATION OF WISCONSIN.

DESIGN FOR A FOLDING CHAIR.

Application filed November 14, 1928. Serial No. 28,875. Term of patent 14 years.

To all whom it may concern:

Be it known that I, FRED P. DANZER, a citizen of the United States, residing at Racine, in the county of Racine, State of Wisconsin, have invented a new, original, and ornamental Design for Folding Chairs, of which the following is a specification, reference being had to the accompanying drawing, forming part thereof.

The figure is a perspective view of the folding chair showing my new design, the shading indicating contrasting colors.

The dominant feature of the design is a futuristic pattern embodying the combination of two sets of triangular shaped sections, one set for the seat and one for the back of the chair, certain of the sections being of contrasting colors.

I claim:

The ornamental design for a folding chair, as shown and described.
